Patented Feb. 23, 1915.

UNITED STATES PATENT OFFICE.

THOMAS J. JARNIGAN, OF DENTON, TEXAS.

CHURN.

1,129,493.

Specification of Letters Patent. Patented Feb. 23, 1915.

Application filed August 17, 1914. Serial No. 857,209.

To all whom it may concern:

Be it known that I, THOMAS J. JARNIGAN, a citizen of the United States, residing at Denton, in the county of Denton and State 5 of Texas, have invented a new and useful Churn, of which the following is a specification.

This invention relates to churning, one of its objects being to provide a churn having two 10 dashers mounted for reciprocation, simple and efficient means being provided for actuating these dashers.

With the foregoing and other objects in view which will appear as the description 15 proceeds, the invention resides in the combination and arrangement of parts and in the details of construction hereinafter described and claimed, it being understood that changes in the precise embodiment of the 20 invention herein disclosed, can be made within the scope of what is claimed, without departing from the spirit of the invention.

In the accompanying drawings the preferred form of the invention has been 25 shown.

In said drawings:—Figure 1 is a view partly in elevation and partly in section of 30 a churn having the present improvements combined therewith. Fig. 2 is a section on line A—B Fig. 1. Fig. 3 is a section on line C—D Fig. 2.

Referring to the figures by characters of reference 1 designates a churn body having a removable cover 2 provided with spaced 35 openings 3 in which the rods 4 of the dashers 5 are adapted to reciprocate. The cover 2 carries a standard 6 in which is fulcrumed a lever 7 having oppositely extending arms of equal length, there being another arm 8 40 upstanding from the center of this lever and provided at its upper end with a weight 9. Links 10 are connected to the ends of the oppositely extending arms of lever 7 and also to the upper ends of the dasher rods 4.

45 Upstanding from the cover 2 adjacent opposite portions of each opening 3 are parallel guide rods 11, these rods being slidably engaged by ears 12 extending in opposite directions from a sleeve 13 secured to the 50 dasher rods 4. A coiled spring 14 is secured to each of the oppositely extending arms of lever 7, these springs 14 being attached at their lower ends to the cover 2.

It will be apparent that by providing dashers with operating mechanism such as 55 described, it is possible to actuate the dashers with the expenditure of but little energy. By pushing against the upwardly extending arm 8, the weight 9 will facilitate the movement of the lever, this movement extending 60 one of the springs 14 so as to place it under stress. During this movement of the lever, one dasher 5 will move downwardly while the other dasher 5 will move upwardly. When the arm 8 is released, the spring 14 65 which is under stress will swing lever 7 back toward its initial position, weight 9 serving to carry the lever past its central or normal position so that but little additional power is necessary to further actuate lever 7 in order 70 to lower the other dasher while the one previously lowered is being raised.

Importance is attached to the fact that all of the mechanism is carried by the cover 2 so that it is thus possible to apply the 75 mechanism readily to one of several churn bodies. The guide rods 11 and the parts engaging the same serve to keep the dasher rods 4 in proper alinement during their operation.

What is claimed is:—

The combination with a churn cover and a standard secured thereon, of dasher rods mounted to reciprocate within the cover, a centrally fulcrumed lever supported on the 85 standard, opposed balanced springs connecting the arms of the lever to the cover, link connections between the ends of the lever and the respective dasher rods, a weighted arm extending upwardly from the center of 90 the lever and at right angles to said lever, said arm being maintained by the springs normally in a vertical position, guides upstanding from the churn cover, and means upon the dasher rods for slidably engaging 95 the guides.

In testimony that I claim the foregoing as my own, I have hereto affixed my signature in the presence of two witnesses.

his
THOMAS X J. JARNIGAN.
